UNITED STATES PATENT OFFICE.

ALVIN M. CRAIG, OF NEW HAVEN, CONNECTICUT.

BUFFER FOR GUNS.

1,356,191.

Specification of Letters Patent. Patented Oct. 19, 1920.

Application filed November 23, 1918. Serial No. 263,803.

To all whom it may concern:

Be it known that I, ALVIN M. CRAIG, a citizen of the United States, and a resident of the city of New Haven, county of New Haven, and State of Connecticut, have invented a new and useful Improvement in Buffers for Guns, of which the following is a full, clear, and exact description.

My invention relates to improvements in buffers for guns, meaning by this term to include all varieties of firearms, and the object of my invention is to produce a simple device which is applicable to various styles of firearms and which is particularly applicable to such guns as employ a bolt in the receiver, the buffer being adapted to disipate and diffuse the shock occasioned by the recoil or backward movement of the bolt. In arms of this type the shock of the bolt as it comes back is detrimental both to the operator and to its effect on the accuracy of the gun. If the gun is a shoulder piece, the blow is such as to make an objectionable kick which gives to the operator a sore shoulder, and furthermore the action, especially on lighter guns, causes the arm to jump so that it is inaccurate in its fire. My invention is intended to overcome these difficulties as stated, and to produce an extremely simple device which can be applied to all firearms of this character, and in which the bolt when near the limit of its stroke strikes the buffer and the latter while having a very small movement, still is able to thoroughly diffuse and dissipate the shock, all of which will be more clearly understood from the description which follows.

Reference is to be had to the accompanying drawings forming a part of this specification, in which similar reference characters indicate corresponding parts in all the views.

Figure 1 is a longitudinal section of the invention showing its application to a part of a receiver and bolt of a gun, and with the parts in the position they assume before the bolt has struck the buffer.

Fig. 2 is a similar view but with the bolt in contact with the buffer and the latter pushed back to its limit, and

Fig. 3 is a cross section on the line 3—3 of Fig. 2.

The bolt 10 can be an conventional or preferred type of bolt which slides in a casing

11 which represents a portion of a receiver, or at least a casing which is made to receive the rear end of the bolt. A second casing 12 which is shown in the form of a nut, is attached to the casing 11, the drawing showing the member 12 screwing into the member 11, and this member 12 has a socket portion 14 in its front end to receive the head 15 of the buffer, the body portion 16 of the buffer sliding through or in the member 12, and the body portion 16 has preferably flattened sides in which are sockets 17 to receive the balls 18, the latter extending for only a portion of their radii into the sockets and running in ways 19 which are made transversely in a wall of the member 12. The balls 18 are pressed to their seats in the member 16 by springs 20, and the springs can be held in any convenient way. As shown a cap 21 screws to the member 12 and covers the several ways 19.

Obviously the member 16 can be of any desired cross sectional shape, and the buffer can be of one diameter throughout instead of having the head 15, but the portion in which the sockets 17 are located is preferably flattened at the points where the sockets are made because in this way I get a better bearing surface of the walls of the socket on the balls, and consequently a better action of the buffer.

When the buffer is in its forward position shown in Fig. 1, the several balls 18 which may or may not be in alinement, are pressed into the sockets 17 preferably for about two-fifths of the diameter of the balls. When the bolt 10 strikes the buffer head 15, the buffer is pushed back slightly and the walls of the sockets 17 pressing against the balls 18 cause the latter to turn and move outward slightly against the tension of their springs 20. I have found in actual practice that the resilience of the buffer is not dependent entirely on the springs 20, but that the shock appears to be dissipated by the rotation of the balls, though the springs also have their cushioning effect. The invention is applicable to various sizes of guns or bolts, and to diffuse thrusts of varying force because the balls can be made larger or smaller and the springs 20 stiffer or lighter as desired.

The experiments which have been made with the buffer have been entirely satisfactory, and in such experiments balls have

been used as the connecting medium between the walls of the buffer and the sockets in the latter.

The balls are set so that they never leave 5 their seats in the sockets, although they do yield slightly against the pressure of their springs, but they spin when under the impact of the blow which tends to force the buffer lengthwise. In this way the energy 10 of the blow is dissipated or diffused in the spinning of the balls which constantly present new surfaces to the impact side of their sockets. I am aware that ball pawls or detents are in very common use, and that cushioned 15 balls entering sockets serve to retain parts against a certain amount of pressure, after which they yield and leave their sockets; but my invention is entirely different in principle from the structures of this 20 character. If the balls were made to leave their sockets they would not serve the purpose intended, but I have found that by having them entered sufficiently to retain their seats and yet yield slightly against their 25 springs, the shock against the buffer is diffused with a very slight longitudinal movement of the buffer. This has been demonstrated by thousands of experiments, and in a gun the shock occasioned by the rearward 30 movement of the bolt is practically all dissipated or diffused, and I have found further that where there is a very heavy shock several of these buffers may be used, one behind the other so that the slight movement 35 of one will be in part taken up by the one behind it, but the buffers are made as shown and I refer to this simply to illustrate a more extended use of the structure.

In guns of the kind here referred to at 40 tention is called to the fact that the rear end of the bolt besides making the gun objectionable for the reasons already pointed out, is apt to become itself battered and useless after a short time because of its violent 45 thrust against the part behind it; but with the buffer described the rear end of the bolt is left uninjured, and a further advantage is that the action of the gun can be slowed or quickened by regulating the springs 50 behind the balls 18, that is if relatively stiff springs are used the action will be speeded because of the quick, sharp reaction of the springs, and if lighter springs are used the action will be retarded. This regulation of

the speed can be further governed by regulating the depth of the ball seats in the buffer body, as obviously the ball will release quicker if the seat is shallow than it will if the seat is deeper.

I claim:—

1. A buffer of the kind described comprising a casing, a member sliding longitudinally in the casing and provided with sockets in its outer surface, and cushioned balls extending into the sockets from the casing 65 sufficiently to retain their seats but spin therein when the buffer is subjected to longitudinal movement.

2. A buffer of the kind described comprising a casing, a member sliding longitudinally in the casing and provided with flattened sides having sockets therein, and cushioned balls held transversely in the casing and entering the aforesaid sockets sufficiently far to retain their seats when the buffer is 75 subjected to endwise movement but to turn in said sockets.

3. A buffer of the kind described comprising a longitudinally sliding member having a guided movement and surface sockets 80 therein, and cushioned balls held opposite the sliding member and entering the sockets sufficiently to retain their seats when the sliding member is subjected to endwise movement.

4. A buffer of the kind described comprising a sliding member having an enlarged head and sockets in its side surface, a casing fitting the sliding member, and cushioned balls arranged transversely in the casing and 90 entering the aforesaid sockets sufficiently to retain their seats under any endwise movement of the sliding member but to turn in their seats.

5. The combination with the sliding bolt 95 and a receiver for the rear end portion of the bolt, of a sliding buffer arranged behind the bolt in position to receive the thrust of the latter, said buffer having sockets in its sides, and cushioned rotary members held 100 opposite the buffer and entering the aforesaid sockets sufficiently to retain their seats under the endwise movement of the buffer but to rotate in said seats.

ALVIN M. CRAIG.
